GAS BURNER AND COMBUSTION CONTROL APPARATUS

Ben Douglass Balthis, Glendale, Calif., assignor to Natural Gas Equipment Inc., Los Angeles, Calif., a corporation of California

Application July 20, 1935, Serial No. 32,386

20 Claims. (Cl. 158—7)

This invention has to do generally with heating and combustion control apparatus, and relates particularly to improvements in gas burner heating units and conjunctive fuel and air control, especially adaptable for industrial units such as 5 boilers, furnaces, retorts and the like.

Among the principal objects of the invention are to provide a burner, or a system of burners, capable of operating at an extremely high degree 10 of heating and combustion efficiency, and capable of maintaining an intense heating and exceptionally uniform temperature condition throughout the entire area of the zone or surface being directly heated. Generally speaking, such efficiency is largely dependent upon maintaining 15 certain exactness in the proportioning and distribution of the primary and secondary air supplied to the burners, and in maintaining a uniformity and stability of temperature conditions at or in the immediate vicinity of the combustion 20 zones where the fuel leaves the burner nozzles. The above of course presupposes a proper control of the fuel and general air supply being fed to the burner.

The first of these conditions is met in accordance 25 with the invention by the provision of a new and improved type of burner and burner assembly, so designed as to give an accurate proportioning of both the fuel and primary air, and the secondary air in relation to the mixture of 30 fuel and primary air. The second mentioned condition is served by providing in conjunction with each burner, or in the burner assembly, heat retaining bodies which serve, despite fluctuation in 35 the combustion rate in the burner, to maintain a closely uniform temperature throughout the entire zone wherein combustion directly is taking place.

With more particular regard to the structural 40 aspects of the invention, one of my primary purposes is to provide a unitary assembly including a burner box containing an assembly of nozzles, and having features of adjustability that enable a box of given size to be installed in combustion chambers or fire boxes whose dimensions may 45 vary within substantial limits, thus obviating the necessity for having to specially design a burner box to fit any particular installation. Another object of the invention is to provide an improved 50 type of burner and burner assembly involving the use of ceramic blocks or fire bricks as heat retaining media whereby the heating and combustion efficiency, as well as the distribution and maintenance of even temperature conditions, are materially improved. Other objects of the inven-

tion pertain to an improved control system for automatically regulating the air supply, and in addition, if desired, the flow of gas to the burners.

All the above mentioned and additional objects and features of the invention will be more fully understood from the following detailed description of the invention in one of its typical and preferred forms. Throughout the drawings reference is had to the accompanying description, in which:

Fig. 1 is a sectional view taken longitudinally of the fire box portion of a boiler and showing the burner assembly, the section being taken on line 1—1 of Fig. 2;

Fig. 2 is a transverse section on line 2—2 of Fig. 1;

Fig. 3 is an enlarged sectional view showing one of the burner nozzles in detail;

Fig. 4 is a perspective showing the burner box and nozzle assembly, together with the gas and air supply control apparatus;

Fig. 5 is a fragmentary view showing the air control door operating diaphragm in section;

Fig. 6 is an enlarged sectional view showing the gas control valve; and

Fig. 7 is a fragmentary perspective showing the arrangement and mounting of the adjustment plates at the corner of the burner box.

In Figs. 1 and 2 I have shown the burner assembly, generally indicated at 10, placed within the combustion chamber or fire box 11 of a typical and conventionally illustrated fire tube boiler B. The boiler shell comprises inner and outer walls 12 and 13 forming the steam chamber 14. Wall 12 encloses the combustion chamber 11, the sides of which are formed by the vertical walls 12a of the inner shell. The particular type and design of the boiler are of course in no way limitative on the invention, since the present burner assembly is capable of installation and applicable for use in various forms of boiler and heating units generally wherein the fire boxes or combustion chambers are adapted to accommodate the burner assembly.

As best illustrated in Fig. 4, the burner assembly 10 comprises a box structure 15 having side walls 16, 17, 18 and 19, and a floor 20. The box 15, together with the later described burner assembly, constitute a unitary structure adapted to be installed within the combustion chamber of a boiler after the latter has been set in position. This type of burner unit has the advantage of being readily removable and capable of reinstallation in other boilers, or in the same boiler where, as in oil field practice, the boiler is being moved

from place to place and used at different wells or locations.

The size of the burner box 15 for any particular installation will be selected roughly to correspond with the cross sectional dimensions of the lower part of the combustion chamber 11. However, due to the fact that the dimensions of the combustion chamber in different boilers may vary considerably, it is impractical to attempt to build the burner boxes in all the various dimensions that would correspond closely to the sizes of the combustion chambers in possible installations. In accordance with the invention, I have provided means whereby a burner box of given size may be made capable of a substantial degree of dimensional adjustability, rendering it adaptable for installation in various combustion chambers of different sizes.

Each of the side walls of the box 15 has a horizontally, and preferably outwardly projecting flange 21 which supports a horizontally shiftable adjustment plate 22, the latter in each instance being guided in its shifting movement and held in adjusted position by bolts 23 on flanges 21 extending through slots 24 in the adjustment plates. Plates 25 may be secured to flanges 21 at the corners of the box to prevent an up-draft of air between the ends of the adjustment plates 22. In installing the burner assembly within the combustion chamber 11, the box 15 is moved in beneath the chamber and then raised to proper height, as shown in Figs. 1 and 2, the box being supported in raised position by any suitable means, such as blocks 26. If necessary, adjustment plates 22 are shifted laterally to substantially close off any space between the side walls 12a of the combustion chamber and the outer edges of flanges 21, thus preventing an up-draft of air around the box and into the combustion chamber. As will readily appear, the range of adjustability of plates 22 is sufficient to enable the spaces around the burner box to be closed off, even though there may be considerable difference in the corresponding horizontal dimensions of the box and combustion chamber. If desired, fire brick 27 may be laid, as illustrated, on plates 22 to insulate the wall of the combustion chamber immediately surrounding the assembly of burners. Preferably, the adjustment plates 22 will be provided at their inner edges with upstanding flanges 28 for the purpose of confining the fire brick 27.

Gas supply manifold 29 is placed within and across one end of the burner box 15, and a series of equally spaced nozzle supply branch pipes 30 extend from the manifold substantially across the box. Each of pipes 30 supports a row of burners 31, the individual burners in each row being equally spaced, and the corresponding burners in the rows being aligned transversely of the box as viewed in Fig. 2. As best illustrated in Fig. 3, each of the burners 31 comprises a nozzle 32 having a Venturi-shaped gas and air mixing passage 33 into which the primary air is drawn through openings 34 by virtue of the velocity of the gas stream being discharged upwardly through bore 35 of the nozzle supporting nipple 36 threaded at 37 within the upset portion 38 of the pipe 30. Bore 32a within the bottom of the nozzle body below the air openings 34 has a sliding fit with nipple 36 so as to enable the nozzle to be slipped over the nipple and rested on the nipple flange 36a. Gas nozzle tip 36b having a calibrated bore 36c is threaded into the

upper end of bore 35, the nozzle projecting upward sufficiently far with relation to the restricted throat 33a of the gas and air mixing passage, to produce the proper aspirating effect in drawing in primary air through openings 34. The fuel and air mixture nozzle 32 and the upwardly flaring passage 33 are sufficiently long that the gas and primary air during their flow through the passage will become intimately and thoroughly mixed to form a combustible mixture of 10 the desired proportions.

A fire brick 40 is supported on each nozzle 32 within the primary air and fuel mixture outlet as defined by rim 41, the sides of this brick being spaced from rim 41 so as to provide an elongated 15 narrow clearance space at 42, substantially entirely around the brick. The latter may be conveniently supported within the nozzle on lugs 43 cast integrally with the body of the nozzle, and having inwardly projecting portions 43a serving 20 to maintain a minimum clearance between the brick and the rim 41 of the nozzle. The fuel combustion thus occurs at the narrow space surrounding the fire brick and at the outer surfaces of the latter so that at all times the brick is heated to substantially the combustion temperature. It may be mentioned at this point that by reason of the capacity of the fire brick for retaining 25 heat, the brick serves to maintain a relatively stable temperature condition at the point of gas combustion regardless of fluctuations in the rate of flow or proportions of the combustible mixture. And, as previously observed, by reason 30 of the maintenance of a relatively uniform high temperature at the point of combustion, a stable 35 temperature condition is established which results in maximum heating and combustion efficiency.

Each of the nozzles 32 also has a series of angular lugs 44 formed on the outside of the side 40 edges of the rim portion 41, these lugs serving to support rows of fire bricks 40a, see Fig. 1, placed between adjacent rows of the nozzles 31, and serving the same general purpose as bricks 40. Lugs 44 also maintain bricks 40a in spaced relation to the outer surfaces of the nozzles so as to allow an up-draft of secondary air through the spaces at 45. As shown in Fig. 2, secondary air is supplied at the ends of the nozzles 31 through spaces 46. The individual burner assembly in each row, as viewed in Fig. 4, may be maintained in proper position and alignment by bars 47 secured to one end of each burner.

In the foregoing it has been observed that the mixture of gas and primary air flows upwardly 55 around the bricks 40 through the clearance spaces 42 within the nozzle outlets. The primary air in the initial combustion mixture formed within the burner nozzles is supplemented by secondary air rising through spaces 45 and 46 60 immediately surrounding spaces 42 within the nozzles, so that a direct and intimate admixture of secondary air with the first formed mixture, is formed at the point of combustion. As in the case of fire bricks 40 contained directly within 65 the nozzles, bricks 40a are directly surrounded by the combustion flame so that all the bricks are subjected to the same condition of direct heating, and all contribute to the maintenance of a 70 uniform temperature condition at the points where combustion is taking place.

The supply of air to the interior of the burner box is controlled by a pair of pivotally movable doors 48 mounted on a shaft 49 journaled in the 75

ends of a box structure 50 projecting from side wall 17 of the burner box 15. The air supplied to the burner box is automatically regulated in accordance with the rate of gas flow to the burners by means of an apparatus, generally indicated at 51, installed in the gas supply line 52 connecting through the wall 16 of the burner box with the manifold 29. The air control apparatus 51 comprises, generally speaking, a gas pressure responsive means operatively connected with the air control door shaft 49 so as to progressively open the doors 48 to admit more air as the gas flow to the burners increases, and to close the doors as the gas flow decreases. I have illustrated a typical form of pressure responsive device comprising a body 53 having sections 53a and 53b, between which is clamped a diaphragm 54, the underside of which is subjected to the gas pressure in line 52 by way of a nipple connection 55. The diaphragm 54 operates a rod 56 yieldably maintained in engagement with the diaphragm by means of coil spring 57. The upper end of rod 56 is pivotally connected at 56a with lever 58 mounted at 59 on fulcrum 60, and lever 58 in turn is connected via links 61 and 62 with shaft 49, the outer end of link 62 being secured to the shaft by clamp 63.

The gas supply to the burner assembly may be controlled by a valve 64, which may be of a manually operated type, or an automatically controlled valve operated in response to variations in the boiler steam pressure by way of a pressure connection 65. Increased flow of gas to the burners results in an increase in the pressure applied to the underside of diaphragm 54, causing the latter to raise rod 56, and through the linkage 58, 61 and 62, to rotate shaft 49 and open the doors 48 to admit more air. Conversely, a decrease in the rate of gas supply to the burners results in a reduction of the gas pressure against diaphragm 54 and rotation of shaft 49 to move doors 48 toward closed position, decreasing the burner air supply.

The fuel and air control system also embodies means for automatically controlling the gas flow to the burners in accordance with changes in gas pressure applied to diaphragm 54. A gas control valve 66 installed in line 52 beyond the diaphragm device 53 in the direction of gas flow, preferably consists of a simple butterfly valve 67 carried on shaft 68 extending through packing gland 69 in the body portion 70. The valve is operated from the air door shaft 49 by way of lever 71 clamped to the end of lever 62, link 72, and lever 73 secured by clamp 74 to the valve shaft 68. As the gas flow through pipe 52 to the burners increases and shaft 49 is rotated due to increased pressure against the underside of diaphragm 54, as previously explained, the valve 67 is progressively opened to permit increased supply of gas to the burners. As the gas flow to the burners is throttled by valve 64 and the pressure against diaphragm 54 is decreased, valve 67 is moved toward closed position to throttle the burner gas supply.

It will be understood that the drawings are to be regarded merely as typical and illustrative of the invention in one of its preferred forms, and that various changes and modifications may be made in the structure illustrated without departing from the true spirit and scope of the invention.

I claim:

1. In apparatus of the character described,

the combination comprising a pair of horizontally spaced upwardly discharging burner nozzles, lugs projecting from the inside and outside of the walls of said nozzles, a fire brick supported on the lugs within each nozzle, and an intervening fire brick supported on the outside projecting lugs of the two nozzles. 5

2. In combination, a pair of horizontally spaced burner nozzles having upwardly opening mouths, a pair of refractory heat retaining bodies, one received and spaced within the mouth of each nozzle and forming gas emission slots in said nozzle mouths adjacent the side faces of the corresponding bodies, and an intervening refractory heat retaining body spaced between 15 said first mentioned refractory bodies, there being upwardly extending air spaces between opposite sides of said intervening refractory body and said nozzles.

3. In combination, a pair of horizontally spaced 20 fuel nozzles having flared rectangular upwardly opening mouths, a pair of fire bricks received within said rectangular mouths, said bricks being supported with their side surfaces in substantially vertical planes, there being narrow upwardly extending gas emission slots between the rims at the upper ends of the nozzles and the lower portions of said bricks, and an intervening fire brick supported between and on the same level with and parallel to said first mentioned fire bricks, and there being upwardly extending air spaces between opposite sides of said intervening brick and said nozzles, opposing side surfaces of said bricks defining two vertically extending combustion spaces for the flame issuing from between the rims of the nozzles and the nozzle received bricks. 30 35

4. A gas burner assembly embodying the combination of: a heat retaining ceramic floor comprised of a plurality of ceramic blocks having substantially flat vertical faces horizontally spaced apart; and a plurality of burners beneath said blocks, marginal portions of the discharge openings of said burners cooperating with certain of said blocks to form gas emission slots 40 45 in the spaces separating the successive blocks.

5. A gas burner assembly embodying the combination of: a heat retaining ceramic floor comprised of a plurality of ceramic blocks having substantially flat vertical faces horizontally spaced apart; a plurality of burners beneath said blocks, marginal portions of the discharge openings of said burners cooperating with certain of said blocks to form gas emission slots 50 55 in the spaces separating the successive blocks; and cooperative means for supporting said burners and said blocks to provide a unitary assembly.

6. A gas burner assembly embodying the combination of a heat retaining floor comprised of a row of refractory blocks having substantially flat vertical faces horizontally spaced apart; and burners positioned beneath the alternate blocks in said row, marginal portions of the discharge openings of said burners cooperating with the said alternate blocks to form gas emission slots 60 65 in the spaces between the successive blocks.

7. A gas burner assembly embodying the combination of a heat retaining floor comprised of a row of refractory blocks having substantially flat vertical faces horizontally spaced apart, 70 burners positioned beneath the alternate blocks in said row, marginal portions of the discharge openings of said burners cooperating with the said alternate blocks to form gas emission slots 75

in the spaces between the successive blocks; and cooperative means supporting said burners and said blocks to provide a unitary structure.

8. A gas burner assembly embodying the combination of a heat retaining floor comprised of a row of refractory blocks having substantially flat vertical faces horizontally spaced apart; and burners positioned beneath the alternate blocks in said row, said burners having flared discharge openings shaped to conform substantially with and to surround the said alternate blocks, thereby forming gas emission slots in the spaces between the successive blocks in said row.

9. A gas burner assembly embodying the combination of a heat retaining floor comprised of a row of refractory blocks having substantially flat vertical faces horizontally spaced apart; burners positioned beneath the alternate blocks in said row, said burners having flared discharge openings shaped to conform substantially with and to surround the said alternate blocks, thereby forming gas emission slots in the spaces between the successive blocks of said row; and internal and external projections on the discharge openings of said burners for supporting all of said blocks.

10. A gas burner assembly embodying the combination of a heat retaining ceramic floor comprised of a plurality of ceramic blocks having substantially flat vertical surfaces; a plurality of burners beneath said blocks, marginal portions of the discharge openings of said burners cooperating with certain of said blocks to form gas emission slots in the spaces separating the successive blocks; and means at the discharge openings of said burners supporting said blocks.

11. A gas burner assembly embodying the combination of a heat retaining floor comprised of a row of refractory blocks having substantially flat vertical faces horizontally spaced apart; burners positioned beneath the alternate blocks in said row, marginal portions of the discharge openings of said burners cooperating with the said alternate blocks to form gas emission slots in the spaces between the successive blocks; and means at the discharge openings of said burners for supporting said blocks.

12. A gas burner assembly embodying the combination of: a heat retaining ceramic floor comprised of a plurality of ceramic blocks having substantially flat vertical surfaces; a plurality of burners beneath said blocks, marginal portions of the discharge openings of said burners cooperating with certain of said blocks to form gas emission slots in the spaces separating the successive blocks; means at the discharge openings of said burners supporting said blocks; and means supporting said burners.

13. A gas burner assembly embodying the combination of: a heat retaining floor comprised of a row of refractory blocks having substantially flat vertical faces horizontally spaced apart; burners positioned beneath the alternate blocks in said row, marginal portions of the discharge openings of said burners cooperating with the said alternate blocks to form gas emission slots in the spaces between the successive blocks; means at the discharge openings of said burners for supporting said blocks; and means for supporting said burners.

14. A gas burner assembly embodying the combination of a heat retaining floor comprised of a row of refractory blocks having substantially flat vertical faces horizontally spaced apart; burners positioned beneath the alternate blocks

in said row, said burners having flared discharge openings shaped to conform substantially with and to surround said alternate blocks, thereby forming substantially straight flame slots adjacent opposite faces of each of said alternate blocks; internal and external projections on the discharge openings of said burners supporting all of said blocks; a gas manifold; and connection means on said manifold supporting said burners thereby providing a unitary portable assembly.

15. A gas burner assembly embodying the combination of: a heat retaining ceramic floor comprised of a plurality of ceramic blocks each having side faces horizontally spaced from the corresponding faces of adjacent blocks, the adjacent faces of successive blocks defining upwardly extending spaces therebetween; and a plurality of burners beneath said blocks and having discharge openings terminating substantial distances below the upper ends of said blocks, marginal portions of said discharge openings cooperating with certain of said blocks to form gas emission slots in the spaces between said blocks.

16. A gas burner assembly embodying the combination of: a heat retaining ceramic floor comprised of a plurality of ceramic blocks each having side faces horizontally spaced from the corresponding faces of adjacent blocks, the adjacent faces of successive blocks defining upwardly extending spaces therebetween; a plurality of burners beneath said blocks and having discharge openings terminating substantial distances below the upper ends of said blocks, marginal portions of said discharge openings cooperating with certain of said blocks to form gas emission slots in the spaces between said blocks and cooperative means for supporting said burners and said blocks to provide a unitary assembly.

17. A gas burner assembly embodying the combination of: a heat retaining ceramic floor comprised of a plurality of ceramic blocks each having side faces horizontally spaced from the corresponding faces of adjacent blocks, the adjacent faces of successive blocks defining upwardly extending spaces therebetween; a plurality of burners beneath said blocks and having discharge openings terminating substantial distances below the upper ends of said blocks, marginal portions of said discharge openings cooperating with certain of said blocks to form gas emission slots in the spaces between said blocks, means at the discharge openings of said burners for supporting said blocks; and means supporting said burners.

18. A gas burner assembly embodying the combination of: a heat retaining floor comprised of a row of refractory blocks horizontally spaced apart to form vertically extending spaces defined by adjacent outside faces on the successive blocks in said row; and a plurality of burners beneath said blocks, marginal portions of the discharge openings of said burners cooperating with certain of said blocks to form gas emission slots in the vertically extending spaces.

19. A gas burner assembly embodying the combination of: a heat retaining floor comprised of a row of refractory blocks horizontally spaced apart to form vertically extending spaces defined by adjacent outside faces on the successive blocks in said row; a plurality of burners beneath said blocks, marginal portions of the discharge openings of said burners cooperating with certain of said blocks to form gas emission slots in the vertically extending spaces, and cooper-

ative means for supporting said burners and said blocks to provide a unitary assembly.

5. 20. A gas burner assembly embodying the combination of: a heat retaining floor comprised of a row of refractory blocks horizontally spaced apart to form vertically extending spaces defined by adjacent outside faces on the successive blocks in said row; a plurality of burners be-

neath said blocks, marginal portions of the discharge openings of said burners cooperating with certain of said blocks to form gas emission slots in the vertically extending spaces, means at the discharge openings of said burners for supporting said blocks; and means supporting said burners.

BEN DOUGLASS BALTHIS.
